United States Patent Office

Des. 199,769
Patented Dec. 8, 1964

199,769

BOAT

Myron T. Stevens, Kenosha, Wis., assignor to Outboard Marine Corporation, Waukegan, Ill., a corporation of Delaware

Original design application Mar. 21, 1962, Ser. No. 69,353, now Design Patent No. 197,363, dated Jan. 14, 1964. Divided and this application Sept. 27, 1963, Ser. No. 76,776

Term of patent 14 years

(Cl. D71—1)

FIG. 1

FIG. 2

FIG. 3

FIG. 4

FIG. 5

Fig. 6.

FIGURE 1 is a perspective view of a boat showing my new design;

FIGURE 2 is a top plan view thereof;

FIGURE 3 is an elevational view of the side opposite that shown in FIGURE 1;

FIGURE 4 is an enlarged front elevational view thereof;

FIGURE 5 is an enlarged rear elevational view thereof;

FIGURE 6 is a bottom plan view thereof.

The dominant features of my design reside in the portions shown in full lines.

This application is a division of my copending appli-

cation, Serial No. D. 69,353, filed March 21, 1962, now Patent Number D. 197,363.

I claim:

The ornamental design for a boat, as shown and described.
